UNITED STATES PATENT OFFICE.

WILLIAM R. MEUTSCH, OF CHICAGO, ILLINOIS, ASSIGNOR TO NEWBURY TIRE & RUBBER CO., OF CHICAGO, ILLINOIS, A CORPORATION OF ILLINOIS.

DESIGN FOR A TIRE CASING.

Application filed April 23, 1924. Serial No. 9,370. Term of patent 7 years.

To all whom it may concern:

Be it known that I, WILLIAM R. MEUTSCH, a citizen of the United States, residing at Chicago, in the county of Cook and State of Illinois, have invented a new, original, and ornamental Design for Tire Casing, of which the following is a specification, reference being had to the accompanying drawing, forming part thereof.

Fig. 1 is a face view of a portion of a tire casing, showing my new design.

Fig. 2 is a side view of a portion of the casing; and

Fig. 3 is a cross section taken at line 3—3 of Fig. 1.

I claim:

The ornamental design for a tire casing, as shown.

WILLIAM R. MEUTSCH.
